CLAIM

The ornamental design for a lighting fixture, as shown and described.

DESCRIPTION

FIG. 1 shows a bottom perspective view of a lighting fixture of the invention.

FIG. 2 shows a cross section elevation view of the lighting fixture, taken through line 2—2 of FIG. 1.

FIG. 3 shows a bottom view of the lighting fixture of FIG. 1.

FIG. 4 shows a front elevation view of the lighting fixture, where the rear elevation view is identical thereto.

FIG. 5 shows a right side elevation view of the lighting fixture, where the left side elevation view is identical thereto; and, FIG. 6 shows a top view of the lighting fixture.

The broken lines are for illustration purposes only and form no part of the claimed design.
